UNITED STATES PATENT OFFICE.

HATHAWAY M. GORSLINE, OF NILES, MICHIGAN, ASSIGNOR TO KAWNEER MANUFACTURING COMPANY, OF NILES, MICHIGAN, A CORPORATION OF MICHIGAN.

METAL FRAME AND INTERLOCKING JOINT.

Application filed November 15, 1919. Serial No. 336,250.

To all whom it may concern:

Be it known that I, HATHAWAY M. GORSLINE, a citizen of the United States, residing at Niles, in the county of Berrien and State of Michigan, have invented new and useful Improvements in Metal Frames and Interlocking Joints, of which the following is a specification.

This invention relates broadly to means for securing structural parts together, and more particularly to means for securing metal parts to each other, though it is not limited in its application to such use. Among its objects are to provide for securing two structural parts together and holding them in fixed but detachable relation; to provide means whereby a structure may be built up in sections by attaching additional parts to the portion already constructed; to provide means whereby a structure may be lengthened not only longitudinally but may be lengthened by having an extension built transversely to the length of the part already constructed; to provide means whereby the top of the structure may be extended to form an overhang; to provide means for supporting a facing plate for the top extension, and such further objects, advantages, and capabilities as will later more fully appear. My invention further resides in the combination, construction, and arrangement of parts illustrated in the accompanying drawings, and while I have shown therein a preferred embodiment, I desire the same to be understood as illustrative only and not as limiting my invention.

While I have shown my invention as used in the construction of a lunch counter or a cafeteria counter, I desire it to be understood that this is done merely because of greater ease and clearness in illustration. This invention is useful not only in connection with counters but in many other structures as, for example, in the construction of commercial bodies of light delivery trucks.

In the drawings annexed hereto and forming part of this specification, Fig. 1 is a perspective view of a lunch counter frame showing in a general way how my invention is applied to such a structure. Fig. 2 is a perspective view of a frame for a cafeteria

counter. Fig. 3 is a perspective view of the top of a post having one of the longitudinal supporting bars connected thereto and the second one detached therefrom. Fig. 4 is a perspective view of a middle or bottom portion of a post with an end of the supporting rail detached therefrom. Fig. 5 is a cross section showing in elevation one of the posts having a supporting rail secured in place and held therein by a locking element. Fig. 6 is a broken section of a post and supporting rail, the two being held in assembled relation by the locking element. Fig. 7 is a plan view of one section of a cafeteria counter showing the manner in which the parts are secured together, taken along the line 7-7 of Fig. 8. Fig. 8 is a vertical section of Fig. 7 showing a frame with top and facing elements in position. Fig. 9 is a plan of the corner extension for a lunch counter and Fig. 10 is a vertical section along the plane indicated by the line 10-10 of Fig. 9.

It should be understood that the lunch counter construction differs from that of the cafeteria counter only in the extension and the size of the top and facing plates.

Referring in detail to the drawings, numeral 1 indicates the front posts and 2 the rear posts of a counter, while 3 refers to longitudinal and 4 to transverse angle bars used in the construction of the counter. Base elements 5 may be used to support the structure, and it is of course understood that the structure of these supporting elements may vary according to what is desired.

The posts are provided with horizontal apertures 6 and spaced but adjacent vertical apertures 7 adapted to receive tongues 8 and 9 respectively. The formation of these tongues will be perfectly obvious from Figs. 3 and 4. It will be seen in Fig. 3 that an angle iron 10 is secured to the inner side of the angle bar 3 or 4, as the case may be, this angle iron having one end, which engages and is secured to an inner face of the angle bar, and its second end provided with a tongue 9 having a slot 11, one face of which is slightly inclined to the vertical so that when the tongue is inserted in the slot 7 and pushed downwardly, the angle iron 10, and with it bar 3, will be drawn tightly against

the post to prevent any looseness of connection. A similar inclination of the inner face of tongue 8 accomplishes the same result for the top connection. The upper ends 5 of the posts are provided with apertures 12 corresponding to horizontal apertures 6, for the reception of tongues 8 of the top rails or bars.

The middle and lower bars may be locked 10 in place by means of resilient clips 6', generally U-shaped in form and having one arm provided with a plurality of reverse curves adapted to engage a wall of the post and hold the parts in position. (See Figs. 15 5 and 6.)

In order to convert a cafeteria counter into a lunch counter, overhangs or extensions are attached to the top ends of the posts by means of extension bars 15 and 16. These 20 extension pieces are secured at one end to short posts 17, as by spot welding, riveting, or the like. It will be noted in connection with extension bars 15 and 16 that they have their outer ends bent downwardly as 25 shown at 15' to furnish a support to which posts 17 may be attached. These extensions have their opposite ends secured to the posts in the same manner that longitudinal and transverse bars 3 and 4 are secured to said 30 posts. Supported by posts 17 are L-shaped supporting plates 18, 19, and 20, the plates 18 and 19 being united to a short corner post 21, which may have slots 12 for connection of the supporting plate but is not so 35 shown, and the plates 19 being provided with cut away portions and tongues 8', corresponding to tongues 8, to engage apertures 12 in the tops of posts 17. The plates 20 are attached to extension pieces 16 in the manner indicated above, and as illustrated in 40 Fig. 9. Upon the flange 22 of these supporting members or plates, 18, 19, 20 may be mounted facing plates 23, as of Vitrolite, having their upper edges engaging the under 45 surface of the top 24 of the counter. These facing plates 23 are held in position by means of corner caps 25 secured in place by means of bolts 26. If the counter is very 50 long, it will be necessary to use several of these facing plates, and their junction will then be covered by a short cover plate similar to plate 27, to be described.

The large face of the counter below the overhang will be covered by facing material 55 23', as shown in Figs. 7 and 8, the joints at the corners of the counter being covered by the angle cover plates 25', and the joints between sections of the facing material being covered by cover plates 27 (Fig. 7), held 60 in place by bolts 26.

Having now described my invention,

I claim:

1. A frame comprising a supporting member having elongated openings disposed at 65 an angle to each other, and a connecting mem-

ber having portions detachably fitting in said openings for connecting said members together, said openings being longer than said portions for permitting movement of the portions to and from fitting position. 70

2. A frame comprising a supporting member having elongated openings disposed at an angle to each other, a connecting member having portions detachably fitting in said 75 openings for connecting said members together, said openings being longer than said portions for permitting movement of the portions to and from fitting position, and a resilient locking element detachably engaging said members for maintaining said members connected together. 80

3. In a structure of the character described, the combination of posts, supporting plates detachably connected to the posts, facing plates resting on said supporting 85 plates and bearing laterally against the outer faces of said posts, binding members overlying the end portions of said facing plates, and means connecting said members to the posts for holding the facing plates in place. 90

4. In a structure of the character described, posts, bars connecting said posts, facing plates resting laterally against said posts, binding members overlying the extremities of said facing plates, said binding 95 members having attaching means by which they are held to the posts, thereby holding the facing plates in place, and a top plate resting on the posts and bars and forming a cover for the structure. 100

5. A frame comprising posts and frame bars, the posts having spaced apertures disposed at an angle to each other, said bars having correspondingly arranged hooks at the ends thereof and extending into said 105 apertures to hold said posts and bars in close engagement, said apertures being elongated in the same direction for insertion and movement of said hooks into and from holding position. 110

6. A frame comprising a post provided with proximately located and spaced slots being respectively vertically and horizontally arranged, and a frame bar having a horizontally arranged tongue engaging the 115 horizontally arranged slot and a vertically arranged tongue engaging the vertically arranged slot.

7. A frame bar comprising a trough-shaped member provided at its ends with 120 tongues bent at nearly a right angle to the direction of the bar, said bar having secured adjacent its ends angle members having tongues extending in the same direction as the first-named tongues and having a slightly 125 inclined face to cause the bar to be drawn into close engagement with a supporting member and to be held in firm relation thereto.

8. A metal frame comprising a plurality 130

- of posts connected by a plurality of bars at right angles to the posts, and a top extension connected to the posts and adapted to support a top plate and an edge facing plate.
9. A metal frame comprising a plurality of posts connected by a plurality of bars at right angles to the posts, and a top extension connected to the posts and adapted to support a top plate and an edge facing plate, the posts being provided with apertures adapted to receive tongues on the bars and extensions, and said bars and extensions having tongues adapted to engage the posts where apertured to hold the parts in assembled relation.
10. A frame comprising a post having spaced and relatively inclined apertures, and a bar having spaced relatively inclined tongues engaging in said apertures for connecting the bar to the post, said apertures being elongated in the same direction for entry and movement of tongues into and from connecting position.
11. A metal frame comprising a plurality of posts connected by a plurality of bars at right angles to the posts, and a top extension connected to the posts and adapted to support a top plate and an edge facing plate, the support for the facing plate comprising an elongated plate bent along longitudinal lines to have in cross section a X -form.
12. In a structure of the character described, a frame comprising hollow posts provided with angularly related elongated apertures in the side walls of said posts, and connecting bars having angularly related spaced hooks at the ends of said bars and extending into said apertures in the posts.
13. In a structure of the character described, a frame comprising hollow posts provided with angularly related elongated apertures in the side walls of said posts, connecting bars having angularly related spaced hooks at the ends of said bars and extending into said apertures in the posts, and locking means to hold the bars in assembled relation with the posts.
14. In a structure of the character described, upright and angularly notched and apertured posts, bars provided at their ends with projections connecting said posts, part of said bars having their upper surfaces flush with the upper ends of said posts whereby to form a substantially smooth upper surface for the frame and to support a top.
15. In a structure of the character described, a frame comprising a plurality of posts having notched and apertured upper ends, supporting bars provided at their ends with tongues engaging the notches and apertures in the posts and positioned to have their upper surfaces flush with the upper ends of the posts, and extension bars provided with tongues cooperating with said notches and apertures to be supported in a position to support an overhanging top.
16. In a structure of the character described, a frame comprising a plurality of posts having notched and apertured upper ends, supporting bars provided at their ends with tongues engaging the notches and apertures in the posts and positioned to have their upper surfaces flush with the upper ends of the posts, extension bars provided with tongues cooperating with said notches and apertures to be supported in a position to support an overhanging top, and connecting and supporting means joining the free ends of the extension bars and to support facing strips.
17. In a structure of the character described, a plurality of posts having notched and apertured upper ends, supporting bars provided at their ends with tongues engaging the notches and apertures in the posts and positioned to have their upper surfaces flush with the upper ends of the posts, extension bars provided with tongues cooperating with said notches and apertures to be supported in a position to support an overhanging top, connecting and supporting means joining the free ends of the extension bars to support facing strips, facing strips supported by said last named means, and joint covering means secured to the posts and covering the joints between the facing strips.
18. In a structure of the character described, posts, bars connecting said posts, facing plates resting laterally against said posts, binding members overlying the extremities of said facing plates, said binding members having attaching means extending through the posts, by which they are held to the posts, thereby holding the facing plates in place, and a top plate resting on the posts and bars and forming a cover for the structure.
19. A frame comprising a post having spaced and relatively inclined apertures, a bar having spaced and relatively inclined tongues engaging in said apertures for connecting the bar to the posts, and a resilient locking member inserted in one of said apertures between a side thereof and said bar to hold the bar in locking engagement with the posts.
20. A frame comprising a supporting member having a plurality of side walls and elongated openings in said side walls, said openings being disposed at an angle to each other, and connecting members having end portions fitting selectively in the openings in any of said side walls for connecting said members together at any side of said supporting members.
21. A frame comprising an upright supporting member having a plurality of side walls and elongated openings provided in said side walls, said openings being arranged

at an angle to each other, and a connecting member having elongated projections arranged at an angle to each other and fitting selectively in the openings of any side wall
5 of said supporting member for connecting said members together at any side of said supporting members.

In witness whereof, I hereunto subscribe my name to this specification in the presence of two witnesses.

HATHAWAY M. GORSLINE.
